DESIGN FOR A COMBINED CIGAR CASE
AND HUMIDIFIER

Oscar E. Dietrich, Lawrence, Mass.

Application May 14, 1946, Serial No. 129,695

Term of patent 14 years

(Cl. D85—2)

To all whom it may concern:

Be it known that I, Oscar E. Dietrich, a citizen of the United States, residing at Lawrence, in the county of Essex and State of Massachusetts, have invented a new, original, and ornamental Design for a Combined Cigar Case and Humidifier, of which the following is a specification, reference being had to the accompanying drawing, forming part thereof.

Figure 1 is a perspective view of a combined cigar case and humidifier showing my new design.

Figure 2 is a cross-sectional view taken on the plane of the line 2—2 of Figure 1.

I claim:

The ornamental design for a combined cigar case and humidifier, as shown.

OSCAR E. DIETRICH.
